UNITED STATES PATENT OFFICE.

ELMER LOVELL SMITH, OF SPRINGFIELD, MASSACHUSETTS, ASSIGNOR TO PACKAGE MACHINERY COMPANY, OF SPRINGFIELD, MASSACHUSETTS, A CORPORATION OF MASSACHUSETTS.

WRAPPING-MACHINE.

1,377,975.

Specification of Letters Patent. Patented May 10, 1921.

Application filed May 20, 1919. Serial No. 298,482.

To all whom it may concern:

Be it known that I, ELMER LOVELL SMITH, a citizen of the United States of America, residing at Springfield, in the county of 5 Hampden and State of Massachusetts, have invented certain new and useful Improvements in Wrapping-Machines, of which the following is a specification.

This invention relates to improvements 10 in wrapping machines and, more particularly, to machines of the type wherein the wrapping is performed by first inclosing the article, except for its ends, in a substantially tubular wrapper leaving end extensions and subsequently inclosing such ends by twisting the end extensions.

Examples of machines of the type mentioned will be found in U. S. Letters Patent Nos. 1,079,012 and 1,226,622, granted 20 November 18, 1913, and May 15, 1917, respectively, on inventions of Henry J. Kempf. Such machines are adapted, primarily, for wrapping confections having the characteristics of molasses kisses, and wrap such articles in the manner above-described.

This invention is concerned with improvements in machines of the general type disclosed in the above-mentioned patents, such as will render the machines capable of wrapping articles which do not possess the characteristics of the articles defined. For example, molasses kisses generally present two substantially square opposite faces which may readily be gripped in the pockets of 30 the wrapping turret to hold them stationary during the operation of the end twist-ers. Moreover, such confections are compressible to some extent and are, in fact, generally compressed in the pockets of the 35 wrapping turret, so that ample surfaces of the confection are engaged by the fixed and movable walls of the pockets of the turret to frictionally hold the confections against rotation during the operation of the 40 end twist-ers, even though the confection does not present the desired square ends. Other articles, such as hard candies for example, are not readily compressible nor do they commonly present square opposed end 45 surfaces. Frequently, they are more or less rounded or even spherical, in which event very little contact, or even point contact 50 only, will be had with the walls of the pocket

unless special means are provided. Hard candies are readily frangible, as distinguished from molasses kisses, and will chip, crack, and break, if allowed to drop, or if sharply impinged. Other articles, such as chocolate creams and the like, must obviously be handled with greater care than are 60 molasses kisses in machines of the type described.

This invention, therefore, has for its object to improve wrapping machines of the type defined to the end that their field of service may be extended to the wrapping of many kinds of articles, which cannot be successfully wrapped by the present machines.

More particularly, it is an object of the invention to improve the article feeding 70 mechanism and to improve the article holding means of the wrapping turret.

Other objects and advantages will appear in the following description and in the 75 illustrative embodiment of the invention in the accompanying drawings, in which—

Figure 1 is a sectional elevational view of a wrapping machine embodying the invention;

Figs. 2 and 3 are perspective views of the 80 article feeding plunger and the guiding member therefor, respectively;

Fig. 4 is a fragmentary plan view of the machine with many parts, unnecessary to an understanding of the invention, removed or 85 broken away;

Fig. 5 is a fragmentary perspective view 90 illustrative of the means for conveying articles to the feeding means;

Fig. 6 is a sectional plan view taken on the line 6—6 of Fig. 1; and

Fig. 7 is a perspective view of an article, as wrapped by the machine.

Inasmuch as the features of this invention are embodied in certain mechanism of 95 the machines shown in the patents above-mentioned, it will be unnecessary to illustrate and describe the complete machine here. Accordingly, only such parts of the complete machine are shown in the drawings as are essential to a clear understanding of this invention, reference being made to the above-noted patents for a full disclosure of those parts of the machine not herein illustrated.

The machine, in general, includes spaced

supporting frames A which rotatably support a wrapping turret 10, having in its periphery a series of pockets, each formed by a stationary wall 11 and a movable wall 12.

5 The walls 12 are yieldingly urged toward walls 11 and are moved away from the latter at certain times by a cam 13. The turret 10 is turned step by step in a clockwise direction (Fig. 1) and the cam 13 successively moves the walls 12 away from walls 11 before the pockets successively come to rest in line with the article feeding plunger 14. Wrappers w are automatically supplied transversely of the turret and between it and the plunger 14. Articles a, such as spherical hard candies, for example, are successively supplied, by means later to be described, to the plunger 14 and subsequently each article is carried by the latter against a wrapper w and into a pocket of turret 10, whereby the wrapper is applied in substantially U-form about the article. A folding blade 15 then swings upwardly and lays down one of the two projecting flaps of the wrapper, after which the turret is turned and the other projecting flap is laid down in overlapping relation upon the first flap by one end of a stationary arcuate plate 16 which encompasses part of the periphery of the turret and holds the folded flaps in overlapping relation until the wrapping is completed. The wrappers w are longer than the articles a so as to leave tubular end wrapper extensions projecting from each end of the article. The wrapping is completed by twisting such extensions during an interval of rest of turret 10, and while the article a is stationarily held in its pocket. This twisting operation is accomplished by rotary end twisters 17 (Fig. 4), one on each side of the turret, which twisters advance toward the turret, grip the end extensions and by their rotation twist the latter to complete the wrapping,—the completely wrapped article then appearing as shown in Fig. 7. After the end twisting operation the turret 10 moves forward one step and cam 13 releases the wrapped article from the turret pocket, and such article falls from the turret upon an inclined delivery chute 18.

The machine, as thus far described, is substantially like that disclosed in the first-named patent except for the end twisters 55 which are fully disclosed in the last-named patent. Reference is made to those patents for a full disclosure of the detailed construction and operation of the elements herein briefly described.

60 The improvements, which render the machine of the class described suitable for wrapping other articles, will now be described. First, it is essential that the articles be held against rotation in their pockets in turret 10 during the operation of the end

twisters 17. When the articles are spherical, as indicated, they cannot be effectively held in the turret 10 unless special means are provided, for, with pockets of the usual type, point contact only between the articles and the walls of the pocket would be had. If the articles are cylindrical, then line contact will be had, but even this is insufficient for an effective gripping of the articles, as will readily be appreciated. Accordingly, the fixed wall 11 of the wrapping pocket is rounded as at 20 to conform to the contour of the article to be wrapped. As shown, the fixed side wall 11 and the fixed bottom wall 21 are joined together by the curved wall 20, to form a seat for the articles and to increase the extent of contact of the articles with the fixed walls of the turret. The movable walls 12, which consist of elbow levers pivoted at 22, are urged toward the fixed walls 11 by springs, as 23, and are provided with yieldable pads 24 of suitable cushioning material, such as rubber for example. Consequently, these pads 24, which will compress somewhat when engaged with the article, will have a substantial area of contact with the articles to effectively hold them against rotation in the pocket. Moreover, the pads 24 prevent chipping or cracking of the articles a as the latter are gripped by the walls 11 for the sharp impingement, which would otherwise be had when walls 12 are released by cam 13, is cushioned by the pads 24.

The means for feeding the articles a into the turret 10 will now be described. The plunger 14 is slidably mounted on the horizontal upper face of a bracket B and is held thereto by a generally U-shaped block 25 (Fig. 3) which is bolted to the bracket. A link 26 connects a lug on the under face of plunger 14 to the upper end of a lever 27 pivoted at 28 to bracket B and such lever is connected intermediate its ends to a cam fork 29, the forked end of which straddles a cam shaft 30. A cam 31 on the latter is arranged to actuate the fork 29 and thus rock lever 27 and actuate plunger 14. The forward end of the latter is forked shaped (Fig. 6) to present two spaced walls 32 between which the article may be received. The walls 32 have lateral extensions 33 against which the outer portions of wrapper w may be held, as the article is inserted in the turret, by clamps 34, operated by cams on shaft 31, all as fully set forth in the second-named patent.

The articles deposited between the forked ends of plunger 14 rest upon the upper horizontal surface of bracket B and there is inset into such surface a pad 35 of cushioning material to prevent chipping or breaking of the articles which fall, as will appear, between such ends. The upper horizontal surface of bracket B is extended as

nearly as is feasible to the periphery of 5 turret 10 by a plate 36 secured to bracket B and the turret 10 comes to rest in such position that the fixed wall 11 of a pocket 10 alines with such plate. Thus, a track is provided along which the articles *a* may be moved by plunger 14 toward and into a pocket of the turret. Side guides, in the 15 nature of two spaced angle iron brackets 15 37, are provided on plate 36 to prevent the articles, which might roll forwardly out of the recess in the forward end of the plunger when the latter is in retracted position, from 20 rolling laterally off plate 36. The spaced 25 walls 32 of the plunger are slotted, as at 38, to receive the upstanding parts of guides 37 and permit the plunger to move forwardly sufficiently to carry the articles into the pockets of the turret. The article engaging 30 portion of plunger 14 is also provided with a pad 39, of cushioning material to insure against injury to the article, when engaged thereby.

To prevent the articles from rolling forwardly, while the plunger is retracted, to such position as to interfere with the feeding of the wrapper *w*, a movable gate 40 is provided. Such gate is reciprocable, substantially vertically, through a slot in plate 36 35 and between the side guides 37. Gate 40 is fixed to the free end of an arm 41, which is fixed to a rod 42 rotatably supported in lugs 43 depending from member 25. Also fixed to rod 42 is a lever 44, which is connected by 40 a link 45 to a lever extension 46 of the described plunger operating lever 27. The movement of the gate is thus tied up with, and controlled by, that of the plunger and the gate-operating connections described are 45 so arranged as to give the gate a relatively quick downward movement so that it is moved below plate 36 before the plunger reaches it.

The means for successively supplying articles *a* to the plunger 14 will next be described. A receiving table 47 is provided for the articles and is supported at one end by one frame A and at the other end by suitable means not shown. Three sides of 50 the table have rims 48 while the fourth side is open to a conveyer, as indicated in Fig. 4. Such conveyer consists of a sprocket chain 49 mounted on sprockets, one of which is shown at 50, and generally U-shaped article receiving parts 51, which are attached in spaced relation to the chain. The chain travels between two spaced plates 52, which close the open sides of the parts 51 and prevent escape of the articles. The chain 49 55 travels above and substantially in the same vertical plane as plunger 14. The articles *a* are combed into the pockets of the conveyer during its upper lap of travel and carried toward the turret 10. The conveyer is 60 driven step by step by gearing 53 from the 65

shaft of turret 10 (Fig. 4), the shaft of the driving sprocket 50 being indicated by reference numeral 54 in this figure. Thus, the conveyer moves, when the turret does, and the gearing 53 is so arranged as to move the 70 conveyer, during each step of movement of the turret, a distance equal to the center to center distance between successive parts 51.

The conveyer comes to rest in the position 75 illustrated in Fig. 1,—one article receiving pocket as 51', being so located that the article *a* must fall therefrom and so that such article can only fall into proper position between the walls 32 of the plunger. Guides 55 and 56, of U-shaped cross-section, encompass the 80 conveyer during its travel around sprocket 50, and prevent escape of the articles during such travel. The lower guide 55 is fixed to a bracket C, which supports the shaft 54 and which in turn is supported from bracket 85 B. The upper guide 56 rests upon the top of guide 55 and has an arm 57 which is pivoted to bracket A, so that the upper guide may readily be swung upwardly to 90 expose the conveyer when desired.

In operation, the articles *a* are combed into the conveyer and carried step by step until their pockets come to rest in the position illustrated in Fig. 1 in connection with the pocket 51', whereupon they fall between 95 the arms 32 of the plunger 14. The gate 40, at such time, is in raised position as illustrated to prevent escape of the articles. A wrapper *w*, having been fed in place between the gate 40 and turret 10, the plunger 100 14 advances and carries article *a* forwardly. As the article *a* approaches the gate 40, the latter is lowered to permit the article to pass and the article is carried against wrapper *w* and into the turret 10. The remaining 105 wrapping operations then proceed in the manner disclosed in the patents above-referred to. After the plunger 14 has, on its return stroke, moved beyond the gate 40, the gate is moved upwardly into the illustrated position prior to the feeding of a 110 succeeding article to the plunger.

The invention has been disclosed herein, in an embodiment at present preferred, for 115 illustrative purposes, but the scope of the invention is defined by the appended claims rather than by the foregoing description.

What I claim is—

1. In a wrapping machine, a turret rotatable in a substantially vertical plane and provided with peripheral pockets for the reception of articles to be wrapped, a plunger to feed articles to the turret and movable to and from the latter, said plunger having a forked end to receive the articles, a vertically movable gate co-operating with such end to provide a pocket in which the articles may be deposited, and means for moving said gate to allow the plunger to carry the articles to the turret. 120 125

2. In a wrapping machine, a turret, a plunger to feed articles and their wrappers into the turret and movable to and from the latter, said plunger having a forked end 5 to partially encompass the articles, means to feed articles to said plunger, a gate co-operating with the plunger to prevent escape of articles fed to the plunger and arranged between the plunger and the wrapper 10 per during the feeding of the articles to the former, and means controlled by the movement of the plunger to open the gate to allow the plunger to carry the article against the wrapper and into the turret.
3. In a wrapping machine, a turret, a support adjacent the turret along which articles may be moved to the latter, a plunger reciprocable along the support and having a forked end to receive the articles, a gate 15 movable through said support and arranged adjacent said end of the plunger when the articles are fed thereto, and means controlled by the movement of the plunger and operating simultaneously therewith to withdraw 20 the gate from the path of the plunger during the article feeding movement thereof.
4. In a wrapping machine, a turret, a plunger to feed articles to the turret and movable to and from the latter, said plunger 25 having a forked end to receive the articles, a gate co-operating with such end to provide a pocket in which an article may be deposited, and means controlled by the plunger to move said gate to allow the plunger to carry the article to the turret.
5. In a wrapping machine, a turret, a plunger to feed articles to the turret and reciprocable toward and away from the latter, said plunger having a recessed end to 30 partially encompass an article, a gate reciprocable substantially at right angles to the plunger and co-operating with the latter to form a pocket into which articles may be fed, and means connecting the plunger and 35 gate to co-ordinate their movements so that the gate is withdrawn from the path of the plunger to permit the articles to pass into the turret and positioned in the path of the plunger during the feeding of the articles thereto.
6. In a wrapping machine, an intermittently operable turret, a plunger reciprocable toward and away from the turret during intervals of rest of the latter to feed 40 articles thereto, said plunger having a recessed end to partially encompass the articles, a gate co-operating with such end to form a pocket for the reception of an article, conveying means movable step by step 45 during the movement of the turret to carry a plurality of articles and successively deliver them to said pocket, and means to move the gate after an article has been delivered to the pocket to allow the plunger to carry 50 the article to the turret.

7. In a wrapping machine, a turret, a plunger to successively feed articles thereto and provided with a forked end to partially encompass an article, a support along which the plunger travels, a gate co-operating with 70 said plunger and support to form a pocket for the articles, means to successively drop articles upon the support, cushioning means provided on the support and upon which said articles fall, and means to move the 75 gate after an article has been fed to the pocket to permit the plunger to carry the article into the turret.

8. In a wrapping machine, a turret, a plunger to successively feed articles thereto 80 and provided with a forked end to partially encompass an article, a support along which the plunger travels, a gate co-operating with said plunger and support to form a pocket for the articles, means to successively drop 85 articles upon the support, cushioning means provided on the support and upon which said articles fall, means to move the gate after an article has been fed to the pocket to permit the plunger to carry the article 90 into the turret, and means provided on the plunger to cushion the engagement of the latter with the article.

9. In a wrapping machine, a revoluble turret, a reciprocable plunger movable in 95 the plane of the turret, said plunger having a forked end to receive articles to be wrapped, a gate co-operating with such end to provide a pocket in which the articles may be deposited, and means to move said 100 gate to allow the plunger to carry the article to the turret.

10. In a wrapping machine, a revoluble turret, a reciprocable plunger movable in the plane of rotation of the turret, said plunger having a forked end to receive 105 articles to be wrapped, a gate co-operating with such end to provide a pocket in which the articles may be deposited and controlled by the movement of the plunger to permit 110 the plunger to carry the article to the turret.

11. In a wrapping machine, a turret, a support adjacent the turret, the turret being adapted to receive and wrap articles delivered thereto from the support, an endless 115 conveyer provided with individual receptacles each adapted to receive one of the articles to be wrapped and deliver the same to the support, and a plunger operable after the delivery of each article to said support 120 by said conveyer for successively delivering the articles to the turret.

12. In a wrapping machine, a turret, a plunger to feed articles to the turret and movable to and from the latter, said plunger having a forked end to receive the articles, a gate co-operating with such end to provide 125 a pocket in which the articles may be deposited, and means operatively connected with the plunger for opening the gate upon 130

forward movement of the plunger and closing the same when the plunger is withdrawn.

13. In a wrapping machine, a turret, a support adjacent the turret, the turret being provided with means to receive and wrap articles delivered thereto from the support, a plunger for successively delivering each article to the turret from the support, and

10 an endless conveyer provided with individual receptacles each adapted to receive one of the articles to be wrapped and deliver the same to the support in position to be engaged by said plunger.

15 14. In a wrapping machine, a turret rotatable in a substantially vertical plane and provided with peripheral pockets for the reception of articles to be wrapped, a horizontal support located adjacent to one side of 20 said turret, a plunger movable across the horizontal support and reciprocable in the plane of the turret for delivering articles to be wrapped from said support to said

turret, and an endless belt conveyer movable in the plane of said turret and located 25 above the support, said conveyer being provided with individual receptacles each adapted to receive one of the articles to be wrapped and deliver the same to said support in position to be engaged by said 30 plunger.

15. In a wrapping machine, a turret rotatable in a substantially vertical plane and provided with peripheral pockets for the reception of articles to be wrapped, a horizontal support located adjacent one side of 35 said turret, a plunger movable across the horizontal support and reciprocable in the plane of the turret, and an endless belt conveyer located above the support and provided with individual receptacles each 40 adapted to receive one of the articles to be wrapped and deliver the same to said support in position to be engaged by said plunger.

ELMER LOVELL SMITH.
